UNITED STATES PATENT OFFICE

CARL F. HAAS, OF SOUTH BEND, INDIANA, ASSIGNOR TO WESTINGHOUSE ELECTRIC & MANUFACTURING COMPANY, A CORPORATION OF PENNSYLVANIA

DESIGN FOR A LIGHTING UNIT

Application filed January 20, 1930. Serial No. 34,189. Term of patent 14 years.

To all whom it may concern:

Be it known that I, CARL F. HAAS, a citizen of the United States, residing at South Bend, in the county of St. Joseph and State of Indiana, have invented a new, original, and ornamental Design for a Lighting Unit, of which the following is a specification, reference being had to the accompanying drawing, constituting a part hereof.

The single figure is an elevational view of a lighting unit showing my new design.

I claim:

The ornamental design for a lighting unit substantially as shown.

In testimony whereof, I have hereunto subscribed my name this 13th day of January, 1930.

CARL F. HAAS.
